UNITED STATES PATENT OFFICE.

WILLIAM P. WYNNE AND JAMES HARRY WYNNE, OF FORT WORTH, TEXAS.

HYDROCARBON-BURNER.

1,330,294.

Specification of Letters Patent. Patented Feb. 10, 1920.

Application filed December 17, 1918. Serial No. 267,165.

To all whom it may concern:

Be it known that we, WILLIAM P. WYNNE and JAMES HARRY WYNNE, citizens of the United States, residing at Fort Worth, in the county of Tarrant and State of Texas, have invented certain new and useful Improvements in Hydrocarbon-Burners; and we do hereby declare the following to be a full, clear, and exact description of the invention, such as will enable others skilled in the art to which it appertains to make and use the same.

The invention relates to burners of the type which include a retort and a burner tube. These burners are ordinarily provided with mixing chambers in which vapor flowing from a jet orifice of the retort and entrained air are blended together in such proportions as to produce a heating instead of a luminous flame, but the invention is applicable not only to blue flame burners, but to burners which produce a luminous flame.

The object of the invention is to avoid the deposition within the retort of a burner of either the luminous or the non-luminous type, of particles of carbon which, under the influence of high temperatures, are segregated from the fuel in considerable quantities. The deposits thus produced within the retort will, in the course of time, choke the retort and thus interfere with the normal operation of the burner.

We have discovered that the aforesaid objectionable formation of carbon deposits, may be avoided by maintaining the temperature within the retort of a burner below the temperature at which dissociation of the fuel takes place, and that a burner operating under these thermal conditions may be operated for an indefinite period without being cleaned. The desired low temperature may be maintained by providing a retort with a protective covering which prevents jets of flame from the burner from directly impinging upon the retort, and by leaving certain portions of the retort exposed to the cooling influence of a medium, such as air. The same result may be wholly or partly attained by the employment of means whereby the heating jets for the retort are caused to impinge more or less directly upon said retort, or whereby certain of said jets may be prevented from impinging upon said retort.

The form of burner which may be employed includes a retort consisting of a direct tubular passage and two symmetrically disposed return passages leading from the rear end of the direct passage and terminating in diminutive discharge openings from which vapor may escape under pressure; perforated or slotted burner tubes disposed in substantial parallelism with the tubular passages of the retort and in alignment with the discharge openings of the retort, said burner tubes being mounted for oscillation upon their longitudinal axes, so that the direction of the flame jets may be varied; a mass of refractory material, which may constitute the base of the burner, disposed in such relation to the retort as to protect it, to a certain extent, from the heat of the flame jets to thereby maintain the temperature of the oil vapor within the retort below the temperature at which dissociation of the vapor and deposition of free carbon occur; and means for supporting the burner tubes in proper relation to the discharge openings in the retort and for adjusting the receiving ends of the burner tubes with relation to said discharge openings.

The burner may contain other novel features of construction, such as are herein-after described.

Referring to the drawings,—

Figure 1 is a front elevation of a burner equipped with two burner tubes and embodying the principal features of the invention.

Fig. 2 is a plan view of the burner shown in Fig. 1.

Fig. 2^a is a view partly in section revealing the construction of a check valve for the supply pipe of the burner.

Fig. 3 is a plan view showing the base of the burner and the retort.

Fig. 4 is a vertical sectional view taken on the line 4—4 of Fig. 1.

Fig. 5 is a sectional view showing the means for sustaining and adjusting the receiving end of a burner tube.

Fig. 6 is a vertical sectional view taken on the line 6—6 of Fig. 1.

Fig. 7 is a sectional view of the burner provided with a single burner tube.

1 is a supply pipe leading from a source of liquid fuel which is preferably under pressure, the pressure being produced either

by gravity or by a body of compressed air. The retort of the burner consists of a direct continuation of the supply pipe 1, and of return pipes 3, 4 which lead from the 5 end 2 of said supply pipe.

5 is the base of the burner which, as shown, is provided with integral supporting flanges forming a space within which the retort is disposed. This base 5, which 10 operates to shield the retort and thereby modify the temperature therein, is preferably made of refractory material to enable it to withstand, without deterioration, the high temperatures to which the same is 15 subjected.

The return pipes 3, 4 of the retort terminate respectively in upwardly extending portions 10, each of which is provided with a discharge opening 11 for the vapor.

20 The burner pipes 6 and 7 are provided with main jet orifices 8, and supplemental jet orifices 9, and are supported a suitable distance above the base 5 by standards 5^a, 5^b, 5^c, two of which, 5^a and 5^c, rise from the 25 ends of the base 5. The standard 5^a is provided with openings 5^a for the reception of the rear ends of the burner tubes, the standards 5^b and 5^c being provided with open seats 5^e and 5^f which admit of the withdrawal of the burner tubes from their supported positions.

A bracket 12 is mounted upon each of the upwardly extending portions 10 of the retort, a set screw 12^a being employed to 30 retain each of said brackets in any desired position of adjustment. Each bracket terminates in a collar 12^b which encircles the receiving end of a burner tube. Should it be desired to remove one of the burner 35 tubes, said tube may be moved longitudinally to free it from the collar 12^b whereupon it may be lifted from the seats 5^e and 5^f and withdrawn from the opening 5^a in the standard 5^a. In placing the burner 40 tubes in position, care should be taken to properly distance the inlet ends of said tubes from the jet orifices, in order to secure a mixture of the vapor and the air which will produce a flame of the desired quality. 45 If the jet orifices should be too near the inlet ends of the burner tubes, the supply of air would be deficient and the flame will be luminous or smoky.

The adjustable character of the bracket 50 12 admits of the true centering of the discharge opening of each of the upwardly extending portions 10 with relation to the corresponding burner tube. This is important inasmuch as the character of the flame of the burner is materially altered by a faulty 55 adjustment of the discharge openings 11 relatively to the inlet ends of the burner tubes. If the jet of vapor should be projected into one of the burner tubes out of 60 coincidence with the axis of said tube or if

the jet orifice were improperly distanced from the inlet of the burner tube the mixture would be imperfect and a more or less non-luminous flame produced.

The burner tubes 6 and 7 are capable of 70 being rotated on their longitudinal axes to any desired extent, the object of rotating them being to vary the direction of the jets of flame emanating from the supplemental orifices 9 in order that the heating of the 75 retort may be controlled. If the positions of the burner pipes are such as to effectuate a direct impingement of the flame jets upon the base 5, the contents of the retort will be highly heated, but if the adjustments of the 80 burner tubes are such as to cause the flame jets to impinge upon the base 5 with considerable obliquity, the heating of the fuel in the retort will be minimized to a considerable extent. Intermediate adjustments 85 of the burner tubes will produce desired variations of temperature within the retort between the aforesaid extremes of temperature. The drawing shows a row of laterally disposed main jet orifices 8 for each 90 tube, but other orifices may be provided as may be found necessary. In some cases it is found desirable to employ only laterally arranged orifices in order that the flame jets may effectuate a distribution of the heat in 95 parts of the combustion chamber which might not otherwise be adequately heated. Each burner tube is preferably provided with a handle 13 which may be manipulated by a suitable instrument to cause the burner 100 tube to rotate to any desired position of adjustment.

The operation of the burner is initiated in a usual manner by heating the same until the liquid fuel in the retort, which may be 105 any volatilizable liquid fuel such as kerosene, is vaporized, and until the resulting vapor escapes under more or less pressure from the discharge openings 11. The oil is preferably introduced into the retort under 110 considerable pressure. The jets of vapor from the openings 11 are projected into the burner tubes 6 and 7 carrying with them by entrainment air which is drawn into the open ends of the tubes 6 and 7 from the atmosphere. During the passage of the vapor and the air through the burner tubes they 115 become more or less thoroughly mixed, and escape from the various orifices of the burner in condition to be consumed by the addition of relatively small quantities of air. The jets of flame originating at the orifices 9 impinge upon the base 5 which by conduction imparts heat received by it to the adjacent portions of the retort. The 120 retort, as already stated, is exposed in part to atmospheric influences which occasion a certain amount of refrigeration. This loss of heat has a tendency to prevent the temperature of the fuel within the retort from 125 130

rising to the dissociating point. The maintenance of a relatively low temperature in the retort may be aided by altering the direction of the heating jets from the orifices 9, this result being attained by oscillating the burner tubes so as to give more or less obliquity to the jets as already described. Under certain conditions these jets may be so directed as to escape impingement upon the base 5, although under ordinary circumstances it will be found necessary to cause the jets to impinge upon said base. The adjustment of the burner tubes will be determined by the apparent temperature of the base 5. If this base becomes red hot it will be known that the impingement of the jets upon the base 5 is too direct, and the burner tubes will then be adjusted to give more or less obliquity to said jets. The retort is never heated to as high a temperature as the base, since the contact between the two elements is more or less imperfect. The tubes of the retort may be connected to the base by a sustaining plate 14 secured in position by bolts 14^a extending through and depending from the base. The base may be provided with concavities 15 to increase the area of contact between said base and the retort.

30 Burners of the type to which the invention is applied are prone to operate pulsatively, the pulsations being due to sequential conversions of increments of the fuel into vapor. The sudden increases of pressure due to this phenomenon cause fluctuations in the flow of vapor from the openings in the retort which lead to irregularities in the flame jets of the burner. These pulsations may be avoided by the employment of a 35 check valve, such as 16, in the supply pipe 1, this valve being set to be closed by pressure within the retort. The valve when closed prevents the flow of vapor through the supply pipe 1, although it allows the 40 fuel to flow gradually and steadily into the retort when the pressure in the retort falls to a certain extent.

A burner containing only a single burner tube and a retort having two vaporizing 45 passages is shown in Fig. 7. In this form of the device the jet orifices 9^a, 9^b of the single burner tube are so arranged that each part of the retort will be acted upon by the flame jets from one set of orifices. The 50 burner may have other jet orifices, such as 8, as in the case of a burner containing a plurality of burner tubes.

Those portions of the burner tubes which 55 intervene between the burner proper and the discharge openings of the retort, are imperforate and of considerable length (16 inches, for instance), the object being to so impede the flow of the current of mixed vapor and air as to allow the proximate jet orifices to be adequately supplied, and to

prevent too much pressure at the remote jet orifices.

Having thus described our invention what we claim as new and desire to secure by Letters Patent is:

1. A burner, including a retort, a burner tube provided with main jet orifices which are directed away from said retort and supplemental jet orifices which are directed toward said retort, a protective covering for a portion of said retort upon which the flame jets of the burner may impinge and means for varying the obliquity of said jet orifices relatively to said retort.

2. A burner, including a retort, a burner tube provided with supplemental jet orifices directed toward said retort, a protective covering for a portion of said retort upon which the flame jets of the burner may impinge, and means for varying the points of impingement of the flame jets.

3. A burner, including a retort and a burner tube, the retort having a protective covering upon which supplemental jets from the burner tube may impinge, and means for maintaining the temperature of the fuel within the retort below the dissociating point of said fuel.

4. A burner, including a base, a retort having tubular portions disposed below said base, and burner tubes arranged above said base and having main jet orifices, and supplemental jet orifices directed toward said base.

5. The combination of a retort having spaced tubular portions, a base disposed above said tubular portions, burner tubes having main and supplemental jet orifices and arranged above said base and in substantial parallelism with said tubular portions, and means for adjusting said burner tubes to vary at will the temperature within the retort.

6. An oil-burning device comprising an adjustable burner tube, having main and supplemental jet orifices, a shielded retort, below said supplemental jet orifices, and a permanently open orifice for discharging vapor from said retort into said burner tube, said burner tube having means for directing the vapor toward said retort.

7. An oil-burning device, comprising a burner tube, a base, a retort disposed below said base and exposed to air on one side thereof, and an orifice for discharging vapor from said retort into said burner tube, said burner tube having main jet orifices directed away from said retort and additional means for directing a portion of the vapor toward said retort.

8. An oil-burning device, comprising a burner tube, a base away from which the main jet orifices of the burner are directed and a retort disposed below said base and having imperfect thermal contact with said

base, said burner having means for discharging relatively limited quantities of vapor toward said retort.

9. An oil-burning device, comprising a burner tube, a base away from which the main jet orifices of the burner are directed, and an air-cooled retort disposed below said base and having imperfect thermal con-

tact with said base, said burner having means for discharging relatively limited quantities of vapor toward said retort.

In testimony whereof, we affix our signatures,

WILLIAM P. WYNNE.
JAMES HARRY WYNNE.
